UNITED STATES PATENT OFFICE.

NATHANIEL J. PRITCHARD AND JAMES S. TEMPLON, OF MILNES, ASSIGNEES,
BY DIRECT AND MESNE ASSIGNMENTS, TO THE PRITCHARD BRAKE
COMPANY, OF ROANOKE, VIRGINIA.

AIR-BRAKE.

SPECIFICATION forming part of Letters Patent No. 399,158, dated March 5, 1889.

Application filed April 13, 1888. Serial No. 270,568. (No model.)

To all whom it may concern:

Be it known that we, NATHANIEL J. PRITCHARD and JAMES S. TEMPLON, citizens of the United States, residing at Milnes, in the county of Page and State of Virginia, have invented certain new and useful Improvements in Air-Brakes; and we do hereby declare the following to be a full, clear, and exact description of the invention, such as will enable others skilled in the art to which it appertains to make and use the same.

Our present invention relates to a device for use in applying pressure to pneumatic railway-brakes, its particular and preferred purpose and use being that of controlling and regulating the admission of air to the brake-cylinder; and it consists, essentially, in the construction, arrangement, and combination of parts, substantially as will be hereinafter described and claimed.

In the accompanying drawings, illustrating our invention, Figure 1 is a vertical section of our improved device for applying pressure to pneumatic railway-brakes, and shows the piston at the upper limit of its stroke. Fig. 2 is a horizontal section on the line xx of Fig. 1. Fig. 3 is a similar vertical section to that shown in Fig. 1, with the piston occupying its lowermost position, or the position taken when the greatest amount of air is being introduced into the brake-cylinder. Fig. 4 is an enlarged perspective view of the semi-cylindrical packing-ring. Fig. 5 is a sectional detail showing the relative position of the piston-rod and its disks, the packing-ring with its ports, and the port leading to the brake-cylinder when a certain fixed amount of pressure is upon the brakes, and is held there with the port closed against the entrance of more air. Fig. 6 is a similar sectional detail showing the arrangement of the same parts when air is permitted to pass through the ports and passages of the packing-ring and onward into the brake-cylinder.

Similar letters of reference designate corresponding parts throughout the different figures.

A denotes a cylinder, of any suitable dimensions and made in any desired manner, it

being preferably adapted to be arranged in an upright position beneath the car or other vehicle with which it is used. It may be made in one or more parts, as preferred. In the drawings a convenient construction is shown, consisting of the main cylindrical body, upon the top of which is a cap-plate, *A'*, securely bolted thereto and formed centrally with a short tubular box, *o*, to receive the upper end of the piston-rod, and thus guide the same during the movements of the piston. The lower end of the main cylindrical body is closed by means of a plate securely fastened over it, and carrying a bulb-shaped air-chamber, *B*, which is adapted to receive at its bottom any drippings or other waste that may accumulate therein, whence they are removable through a drain-cock, *a*.

The cylinder *A* is provided with ports at points where the several pipes are coupled, that are used with the ordinary air-brake and lead to the essential parts of the same.

Thus *C* denotes the port where a coupling is made with the pipe that leads to the air-drum or auxiliary cylinder.

D is the port where the pipe is connected leading to the brake-cylinder.

E is a port situated in the wall of the bulb *B* at a point where it is entered by pipe *F*, that leads to the main air-supply pipe, and through said pipe *F* air is introduced into the device. At port *D* is connected a T-shaped pipe, having a horizontal portion extending outward from the cylinder *A*, at right angles to which portion is another horizontal part, *H*, a plug-valve, *H'*, being located at the junction of these two horizontal parts. This valve will be ordinarily turned in the position shown in Fig. 2, where air may pass in one direction or the other between the port *D* and the pipe *I*, leading to the brake-cylinder and coupled to one end of the pipe *H*.

A short distance below the port *D* in the wall of the main body *A* is located an exhaust-port, *e*. Through this exhaust-port the air from the brake-cylinder will have free egress when the brakes are relieved. A vertical passage, *c*, extends upward through the wall of the cylinder *A* to the port *C*, said passage *c*

having a communication near the bottom of the cylinder by port *d* with the interior of the cylinder *A*. Through the port *d* air coming under pressure from the main supply-pipe 5 will pass into the passage *c* on its way to the air-drum.

Within the central chamber of the device is located a suitably-constructed piston, *J*, adapted to move vertically. To the piston *J* 10 is connected a vertical piston-rod, *G*, whose upper end is received into the tubular box *o*, above mentioned. The piston *J* is located near the bottom of the cylinder *A* and reciprocates within narrow limits in that portion of 15 the cylinder, the upper limit of its movement being shown in Fig. 1, and its lowermost position being seen in Fig. 3. The piston-rod *G* is provided with two flat circular plates or disks secured horizontally thereto at a suitable 20 distance apart and at proper points in the length of the rod, the upper of these plates being denoted by *L* and the lower by *K*. Between these two horizontal plates *K* and *L* is located a semi-cylindrical or semi-annular 25 valve, *M*. It is shown in perspective in Fig. 4. It has a semicircular groove along one side, which receives the piston-rod. It has a radius of sufficient length to enable it to be situated closely between the wall of the main 30 body *A* and the piston-rod, although the fitting is loose enough to enable the said ring *M* to have free movement up and down. A semi-ring is used instead of a complete ring, in order 35 to make the device cheaper and lighter, and for the purposes of its construction it will serve equally well with a completely annular ring. This valve *M* may vary in size, structure, and shape without departing from the spirit of our invention. Its vertical length is 40 shorter than the vertical length of the annular space between the plates *K* and *L*, within which it is contained, as will be evident upon inspection of the figures of the drawings; hence it will be perceived that the piston with 45 its piston-rod, and consequently the plates or disks *K* and *L*, may have a certain amount of vertical movement without displacing the valve *M* from its position. Said valve *M* is furthermore provided with a vertical groove, 50 *g*, in its outer surface, into which groove projects a screw or pin, *h*, fixed in the wall of the cylinder *A*. By means of this pin entering the groove *g* the valve *M* may move vertically without being susceptible of any 55 rotary displacement; also, the valve is recessed on its outer face at *m*, as also at *m'*. The recess *m* is cut out for a portion of the circumferential distance of the valve, and is of sufficient size so that when the valve is adjacent to the ports *D* and *e*, as shown in Fig. 1, they may be connected, thus allowing the air 60 to be exhausted from the brake-cylinder. 65

The under or bottom surface of the valve is provided with a port at *b'*, and the outer surface of the valve is furnished with another port at *b''* in the recess *m'*. The ports *b'* and *b''* are connected by a passage, *b*, running

through the material of the valve. The direction of this passage is of course unimportant; but for convenience in construction it 70 preferably partakes of that direction shown in the drawings, where it runs vertically and then horizontally. The port *b'* is adapted to be closed by the disk or plate *K*. Said port has a packing of suitable material—such as 75 leather, gum, rubber, or other suitable substance—so that a tight joint may be effected. The port *b''* is adapted to come into coincidence with the port *D* during the upward and downward movements of the valve. Doubtless the construction of the valve may vary 80 as experience dictates; but it is thought that the general outline of this construction, as indicated herein, will suffice to explain and define the essential features of its structure and 85 the main purposes of its use.

The operation of the device herein described is as follows: Suppose the piston to be in the position shown in Fig. 1, where it is at its uppermost limit. The semi-ring now rests upon the lower plate, *K*, the port *b'* being closed. It may be noted in this connection that as the piston moves upward the disk *K*, by pressing on the packing-ring, pushes it up. As the piston moves downward, the disk *L*, being in contact with the ring *M*, assists it to descend. In Fig. 1 air is entering the device through the pipe *F*, passing upward beneath the piston *J*, thence out through port *d*, and along passage *c* into port *C* and into the air-drum. 90 The pressure of the incoming air is sufficient to uphold the piston and its connections.

Suppose now that it is desired to set the brakes. The engineer will determine the amount of pressure which he desires to apply 105 to the brakes and adjust his regulating-valve accordingly. Whether a greater or less pressure is needed will of course depend upon the circumstances of the case. The proper manipulation of the engineer's valve will exhaust air from beneath the piston *J*, so that said pressure beneath the piston will be less than the pressure above it. Consequently the piston will begin to descend, thus causing the disk *L* to come in contact with the valve 110 *M* and the disk *K* to be removed from the position where it closes the port *b'*. As the piston continues its descent, the valve will be pushed downward until at length the port *b''* in said valve *M* will come into coincidence 115 with the port *D* in the manner shown in Fig. 6. Air will now begin to pass through the port *b'* and upward through the valve, then out through port *b''* into port *D* and onward to the brake-cylinder, where it will act to set 120 the brakes. The continued outflow of air to the brake-cylinder will in a short time cause the air-pressure in the air-drum and above the main piston *J* to be less than the air-pressure beneath the piston, it being remembered that the port *d* is now closed, so that air in the air-drum is not subject to increase at this time. The result of this 125 inequality of pressures on the upper and lower

faces of the piston will be to cause the latter to adjust itself slightly; hence it will ascend a little, just sufficient to close the port b' and prevent the outflow of any more air, although the movement of the piston will not be sufficient to displace the valve from position. The relation of the parts at this time is clearly shown in Fig. 5, where the disk K is covering the port b' and excluding any more air from entering it. The brakes are now set with a certain pressure of air, and this pressure of air will be maintained steady and constant until the engineer wishes to change the condition of things and again manipulates his valve. By the use, therefore, of this valve, constructed as described and so related to the other parts of the invention as we have indicated it, the amount of air which is admitted to the brake-cylinder may be graduated, regulated, and governed completely, so that the engineer is enabled to set the brakes at a certain desired pressure and keep them at this pressure until he wishes to release them.

25 When the engineer desires to relieve the brakes, enough air will be admitted below the piston J to drive it upward, causing it to resume the position shown in Fig. 1, where the recess m in the valve connects the port D and the exhaust e . Egress of air in the brake-cylinder can now easily take place by passing in the direction of the arrow shown in Fig. 1 through ports D and exhaust e .

When the engineer wishes to apply to the brakes the full amount of pressure of which his apparatus is capable, he will exhaust enough air from below the piston J to compel it to assume its lowermost position, as shown in Fig. 3. In this position the air will not pass through the valve, but will rush directly, as shown by the arrows, from the interior of the cylindrical body A , through port D , to the brake-cylinder.

Having thus described our invention, what we claim as new, and desire to secure by Letters Patent, is—

1. In a device for applying and relieving the pressure on pneumatic railway-brakes, the combination of the inclosing-case having ports leading to the air-drum, main pipe, and

brake-cylinder, an exhaust-port, and a vertical passage extending upward through the wall of the cylinder to the port that leads to the air-drum, said passage having communication near the bottom of the cylinder by a 55 port with the interior of the cylinder, the cap-plate for the cylinder provided with a downwardly-extending tubular box, the piston and its piston-rod, the upper end of which is received into said tubular box, the two flat circular plates or disks secured upon said piston-rod, the valve located between said plates, and consisting of a semi-cylindrical piece of metal having a port in the bottom and a port 60 in the side, which ports are connected by an air-passage, the opening to the lower or bottom port being controlled by the flat plate beneath it, all the parts being arranged to operate substantially as and for the purpose herein described. 70

2. In a device for applying and relieving pneumatic pressure on railway-brakes, the combination of the main cylindrical case A , having the port C , leading to the air-drum, port D , leading to the brake-cylinder, port E , 75 leading to the main air-supply pipe, an exhaust-port, e , and a vertical passage, c , extending upward through the wall of the cylinder to the port C , said passage c communicating by port d with the interior of cylinder 80 A , the cap-plate A' for the main body A , provided with a downwardly-projecting tubular box, o , the piston J and its piston-rod G , whose upper end enters the tubular box o , the two flat circular plates K and L , secured upon the 85 piston-rod, the valve M , located between said plates or disks, and having a bottom port, b' , a lateral port, b^2 , and a connecting-passage, b , between said ports, the port b' being adapted to be closed or opened by the disk or plate K , 90 all the parts being arranged for joint operation, substantially as described, and for the purpose specified.

In testimony whereof we affix our signatures in presence of two witnesses.

NATHANIEL J. PRITCHARD.
JAS. S. TEMPLON.
